UNITED STATES PATENT OFFICE.

JOHN W. COLLIER, OF LOCKPORT, NEW YORK.

OIL-PAIL.

SPECIFICATION forming part of Letters Patent No. 269,014, dated December 12, 1882.

Application filed September 27, 1882. (No model.)

To all whom it may concern:

Be it known that I, JOHN WILLIAM COLLIER, of Lockport, in the county of Niagara and State of New York, have invented a new and 5 Improved Oil-Pail, of which the following is a full, clear, and exact description.

The object of my invention is to provide a new and improved receptacle for oil, which receptacle can be filled easily, and from which 10 the oil can be drawn readily.

The invention consists in the peculiar construction and arrangement of the parts, as hereinafter more fully set forth, and pointed out in the claims.

15 Reference is to be had to the accompanying drawings, forming a part of this specification, in which similar letters of reference indicate corresponding parts in all the figures.

Figure 1 is a front elevation of my improved 20 pail. Fig. 2 is a plan view of the same. Fig. 3 is a cross-sectional elevation of the same. Fig. 4 is a longitudinal sectional elevation of the faucet. Fig. 5 is a sectional plan view of the same. Fig. 6 is a longitudinal sectional 25 elevation of the upper end of the combined vent-tube and faucet-handle. Fig. 7 is a longitudinal sectional elevation of the filling-opening and the strainer and plug in the same. Fig. 8 is a plan view of the strainer in the 30 same.

The pail A, which can be made of wood or metal, has one side made flat, so that it can be placed very closely against a wall, tank, &c. The cover B is fixed in the top of the pail. 35 The bail C is pivoted to the cover, and is provided with a wooden handle, D, semicircular in cross-section, (see Figs. 1 and 3,) and provided with a longitudinal groove, a', for the reception of the top of the bail. The handle 40 is held in place by bends a in the bail, at the ends of the handle. At the middle of the handle D the bail C forms a loop, E, projecting from the top of the handle.

A short tube, F, is secured in an aperture 45 in the cover B, into which tube a plug or stopper, G, fits, which is provided with a handle-loop, G'. A strainer, H, fitting in the tube F, is secured to a wire, H', the upper end of which is bent over to form a hook, H², which is adapted 50 to catch on the upper edge of the tube F and hold the strainer in place while the oil is being poured through it into the pail. The pail

is filled through the tube F, and the strainer H serves to prevent impurities and other solid foreign matter from passing into the pail.

A tube, J, passes through the cover B to the bottom of the pail, and is provided at its upper end with a handle, K. A threaded collar, L, is secured in the cover of the pail, and a threaded sleeve, M, secured on the tube J, screws into the said collar, so that by turning the tube J the same will be raised and lowered. The tube J is guided by two eyes, N, through which it passes, the said eyes being secured to a vertical piece of wood, O, in the pail. 65 The lower end of the tube J is provided with a packing, P, which is set into the tube. An annular packing, Q, on which the lower end of the tube J rests, is countersunk in the bottom of the pail, and is surrounded by a short vertical collar, b, which projects slightly from the upper surface of the bottom of the pail, and is secured to a countersunk ring, d, which holds the said packing Q in place.

The collar b is provided with a series of apertures, e. The faucet-tube R, which is held in the bottom of the pail and projects from the same, has its inner end turned upward so that the inner end projects slightly above the packing Q, as shown in Fig. 4.

The tube J is provided, directly below the cover B, with a side aperture, f, directly below which a plug, g, is driven into the tube to prevent oil from running down the tube. The tube J is also provided above the cover B with two vents, S and T, both of which are closed by ball-valves h and j, with or without springs, or by any other suitable valves.

If the pail is made of wood, the inside is provided with a coating of a solution of glue to 90 prevent the oil penetrating the wood.

The operation is as follows: When the pail is being filled through the tube F the air in the pail passes through the aperture f in the tube J, raises the ball-valve j, and escapes 95 through the vent T. When the lower end of the tube J rests on the packing Q the packings P and Q form a close and tight joint, and prevent the oil from passing into the faucet-tube R. If the tube J is turned in one direction, it will be raised, and the oil can pass from the pail into the faucet-tube R. When the oil is being drawn from the pail the air can enter through the vent S by raising the ball-valve h,

and from there passes through the tube J and the aperture *f* into the pail. The faucet proper is thus in the inside of the pail, but can be operated from the outside. The eye E in the bail C facilitates hanging the bail to a hook on a wall, tank, &c., the flat side of the pail resting against the said tank, &c. The pail can also be used for other liquids as well as for oil.

10 Having thus fully described my invention, I claim as new and desire to secure by Letters Patent—

1. The combination, with the pail A, of the handle D, semicircular in cross-section, and 15 provided with the longitudinal groove *a'*, and hinged bail C, having the bends *a a*, substantially as shown and described.

2. The combination, with the pail A, of the cover B, the filling-tube F, the strainer H, and 20 the hooked wire H', substantially as herein shown and described, and for the purpose set forth.

3. The combination, with the pail A, of the tube J, the faucet-tube R, the piece of wood 25 O, and the eyes or loops N, through which the tube J passes, and which are secured to the piece of wood O, substantially as herein shown and described, and for the purpose set forth.

4. The combination, with the pail A, of the tube J, the packing P in the lower end of the 30 tube J, and the packing Q, surrounding the inner end of the faucet-tube R, substantially as herein shown and described, and for the purpose set forth.

5. The combination, with the pail A, of the 35 tube J, the packings P and Q, the faucet-tube R, and the collar *b*, provided with apertures *e*, substantially as herein shown and described, and for the purpose set forth.

6. The combination, with the pail A, of the 40 tube J, provided with an aperture, *f*, and vents S T, and of the plug *g* in the tube J below the aperture *f*, and faucet-tube R, substantially as herein shown and described, and for the purpose set forth.

7. The combination, with the pail A, of the 45 tube J, provided with the two vents S and T, containing the ball-valves *h* and *j*, respectively, and faucet-tube R, substantially as herein shown and described, and for the purpose set forth.

JOHN WILLIAM COLLIER.
